CLAIM

The ornamental design for a golf glove, as shown and described.

DESCRIPTION

FIG. 1 is a back thumb-side perspective view of the golf glove of this invention;

FIG. 2 is a plan view of the back thereof;

FIG. 3 is a detail view of a portion of the back thereof;

FIG. 4 is a thumb-side elevation view thereof;

FIG. 5 is a small-finger-side elevation view thereof;

FIG. 6 is a plan view of the front thereof;

FIG. 7 is an elevation view of the closed finger-tip end thereof;

FIG. 8 is an elevation view of the open wrist end thereof;

FIG. 9 is a back thumb-side perspective view of another embodiment of the golf glove of this invention;

FIG. 10 is a plan view of the back of the glove of FIG. 9; FIG. 11 is a detail view of a portion of the back of the glove of FIG. 9;

FIG. 12 is a thumb-side elevation view of the glove of FIG. 9;

FIG. 13 is a small-finger-side elevation view of the glove of FIG. 9;

FIG. 14 is a plan view of the front of the glove of FIG. 9; FIG. 15 is an elevation view of the closed finger-tip end of the glove of FIGS. 9; and,

FIG. 16 is an elevation view of the open wrist end of the glove of FIG. 9.

The logo appearing on the closure flap of the glove shown in lighter broken lines, as well as the circle in which it is enclosed and all other lighter broken lines, are features representing environmental subject matter that form no part of the claimed design. All remaining dashed lines are representative of stitching that forms part of the claimed design.
